ATTORNEY

UNITED STATES PATENT OFFICE.

ABRAHAM FELLDIN, OF ITHACA, NEW YORK.

MUSIC-RACK FOR PIANOS.

SPECIFICATION forming part of Letters Patent No. 307,933, dated November 11, 1884.

Application filed July 27, 1883. (No model.)

To all whom it may concern:

Be it known that I, ABRAHAM FELLDIN, a citizen of the United States, and a resident of Ithaca, in the county of Tompkins and State 5 of New York, have invented certain new and useful Improvements in Music-Racks for Upright Pianos, of which the following is a specification.

The object of my invention is to provide an 10 improved construction and combination of devices whereby the raising of the fall-boards to uncover the keys on an upright piano will cause the vertical front to be thrown forward at a suitable inclination for use as a music- 15 rack, which will not only accommodate the player, as in pianos as heretofore constructed, but give plenty of room for the text and music of one or more vocalists or instrumentalists singing or playing together with the pianist, the aforesaid throwing forward and thereby opening of the vertical piano-front at the same time allowing and facilitating the free propagation of the sound from the instrument, as will be hereinafter described with 20 reference to the accompanying drawings, in which—

Figure 1 represents a vertical section of the front portion of an upright piano constructed according to my invention, and showing in 25 full lines the piano closed and in dotted lines the fall-board raised and the front in position when used as music-rack. Fig. 2 is a similar detail section showing the inside of one of the cheeks of the case. Fig. 3 is a similar detail 30 section showing a modification in the hinging of the fall-board to the cheek of the case.

A is the piano-case; B the ordinary lid. a are the keys, and b is the key-frame. C is one 35 of the cheeks of the case, and c' the lock-board. D is the outer and E the inner fall-board, hinged together at c', in the usual manner; but the outer fall-board, D, instead of being supported by the hinge c', is provided on the under side, at opposite ends, a distance 40 below and a little in front of the hinge c', with lugs d, and is hinged or pivoted to the cheeks C by pins or screws i, going through holes in the said lugs D and into the said cheeks C.

The inner fall-board, E, instead of being secured 45 stationary to the cheeks C, is provided

at either end with a projecting pin, e, which pins enter into slots or grooves c on the inside of the cheeks C. The grooves c are preferably curved, as shown in the drawings, and inclining forward, and are covered up by the 55 ends of the inner fall-boards, E, when the piano is closed. By this construction it is evident that the inner fall-board, E, may be slid downward and forward in the grooves c, as well as oscillated upon its pivots, so as to assume any 60 position governed by the raising of the outer fall-board, D, around its pivot i, the inner board, E, being pivoted to the outer by the aforesaid hinges c'.

In the rear of and below the board E is pivoted 65 a lever, G, in such a manner that the lower end, g, of said lever is in contact with the board E, and the upper end, H, (which is preferably made of a bent rod or coarse wire,) in contact with the inside of the lower portion 70 of the front F. The said vertical front F of the piano is provided at opposite ends of its upper portion, on the inside thereof, with lugs f, by which and pins b', going through said lugs and secured to the opposite ends of the 75 frame A, the said front F is supported and pivoted so as to enable it to be swung forward to assume an inclined position suitable for a music-rack. For this purpose the lower edge of the vertical front F is provided with a 80 slightly-recessed shelf, f', on which the music books and papers may be supported.

The lug f, instead of being merely perforated to receive the pin b', is preferably slotted, as shown in Fig. 1, the lower end of the slot being 85 open, so that the front F, when the lid B is raised, may be conveniently removed by simply being lifted off from the pins b'. As the pivoting-point is situated at a distance from and inside of the front F, the weight of 90 the latter will cause it to assume the vertical position shown in full lines when not kept forward by the upper ends, H, of the levers G. When lifting the outer fall-board, D, from contact with the upper edge of the lock-board c' 95 and throwing it back in its dotted position, the inner fall-board, E, will slide by its pivots c downward in the slots c, and at the same time turn upon its pivots until it has assumed the dotted position in Fig. 1. In moving 100

thus the said inner board, E, will depress the forward or lower end, *g*, of the lever G, thereby causing its upper end, *H*, to press the vertical front F forward into its inclined position, the boards D E, lever G, and front F then occupying the relative positions indicated in dotted lines in Fig. 1. It will be seen that the mere uncovering of the keys by raising the fall-board D simultaneously opens the front F, allowing free propagation of the sound from the instrument, and places the said front F in position for use as a music-rack. On again closing the fall-board D all the movable parts resume simultaneously the positions shown in full lines in Fig. 1.

In order to facilitate the closing up of the instrument, the fall-board D is provided on the inside, along its lower edge, with a bead, *d'*, by which the fall-board, when in its raised position, may conveniently be pulled forward to close it.

To facilitate the insertion and removal of the fall-boards D E, the lugs *d* of the board D are slotted, as shown at *d'* in Fig. 3, and the inclined slots *c* are open at their upper ends, as shown in Figs. 1 and 2, so that to remove the fall-boards it is only necessary to raise the outer board, D, off from its pivots *i*, then fold it over the hinges *c'* down upon the inner board, E, and slide the latter upon its pivots *e* up and out of the slots *c*. The insertion of

the boards is of course effected in a similar but reverse manner.

The space for receiving the name of the manufacturer or owner, &c., is on the under side 35 of the outer fall-board, D, which latter, when opened, thus forms the name-board.

Having thus described my invention, I claim as new and desire to secure by Letters Patent—

1. The combination of the fall-boards E D, 40 hinged together, the inner fall-board, E, being provided with pivots *e*, to slide and turn in the slots *c*, and the outer board, D, being supported on end pivots, *i*, with the hinged or pivoted piano-front F, and the lever G, arranged with its ends *H* and *g* in contact with the front F and the board E, respectively, substantially as and for the purpose set forth.

2. The combination of the fall-boards D and E, hinged together, with the cheek-pieces C, 50 the board D having lugs *d*, open at *d'*, to rest on the pivots *i* on the cheeks, and the board E having pivots *e*, to slide and turn in the slots *c* in the cheeks, substantially as set forth.

In testimony that I claim the foregoing as 55 my invention I have signed my name, in presence of two witnesses, this 16th day of July, 1883.

ABRAHAM FELLDIN.
